UNITED STATES PATENT OFFICE.

GEORGE E. HULSE, OF NEW HAVEN, CONNECTICUT, ASSIGNOR TO SAFETY CAR HEATING & LIGHTING COMPANY, A CORPORATION OF NEW JERSEY.

COOLING APPARATUS.

Application filed February 8, 1922. Serial No. 534,878.

This invention relates to cooling apparatus and more particularly to apparatus for cooling drinking water and the like. One of the objects of this invention is to provide a practical and reliable apparatus of the above type and having a reliable and efficient action. Another object is to provide apparatus of the above character in which the several elements are so related mechanically, and in which the mechanical as well as refrigerating or cooling action thereof may take place in such manner, that a substantially unitary and self-contained structure is attained. Another object is to provide a reliable and effective system of lubrication for apparatus of the above nature. Another object is to provide a practical arrangement for mounting and correlating the several elements to provide the above mentioned unitary and self-contained mechanical structure. Other objects will be in part obvious and in part pointed out hereinafter.

The invention accordingly consists in the features of construction, combination of elements and arrangement of parts which will be exemplified in the structure hereinafter described and the scope of the application of which will be indicated in the following claims.

In the accompanying drawings in which is shown one of various possible embodiments of this invention,

Figure 1 is a vertical central section of the lower portion of the apparatus showing the driving motor compressor and related parts in assembled relation with respect to one another; and

Figure 2 is a similar vertical central section of the upper portion of the apparatus showing the reservoir and certain related parts.

Figure 3 is a plan view on a smaller scale of a receiver, certain portions being broken away to show certain features more clearly; and

Figure 4 is a side elevation, partly broken away, of the receiver as viewed from the left in Fig. 3.

Figure 5 is a detailed view partly in section of an expansion device;

Figure 6 is an end view; and

Figure 7 is a vertical cross-section on the line 7-7 of Fig. 6 showing on an enlarged

scale the construction of an expansion unit forming part of the expansion device illustrated in Fig. 5.

Similar reference characters refer to similar parts throughout the several views of the drawings.

Referring now to Fig. 1 of the drawings, there is shown at 10 the main frame or field frame of an electric motor, the lower end being provided with suitable outwardly directed lugs 11 adapted to form a standard or base for supporting the motor frame 10 in a vertical position. A suitable number of lugs 11 are provided to form a rigid support or base and suitable openings are provided in the lower end of the frame and intervening the lugs 11 for a purpose to be hereinafter more clearly set forth. The field frame 10 is provided with a lower or end piece 12 preferably integrally formed therewith and terminating in a housing 13 in which is adapted to be received the outer race 14 of a combined radial and thrust ball bearing whose inner race 15 is suitably mounted and secured to the lower end of the armature shaft 16 of the motor, thereby forming a support for one end of the rotatable part of the motor. The housing 13 is interiorly threaded to receive the exteriorly threaded cap 17 whose inner end is adapted to engage and support the outer ball race 14 which, as will be clear from the foregoing, fits snugly within the cylindrical housing 13. The ball race 14 and with it the entire ball bearing and the armature shaft 16 may thus be not only readily assembled but also readily and conveniently adjusted in an axial direction by means of the threaded cap 17 whose position within the housing 13 may be fixed after adjustment by means of suitable screws 18 threaded into the end of the housing 13 and extending through suitable serrations in the outer periphery of the flanged portion of the cap 17.

Turning now to the support for the other end of the armature shaft 16 it will be noted that the field frame 10 of the motor is provided with a plurality of upwardly and outwardly extending arms 19 terminating in the ring portion 20 whose upper and interior faces may be machined concentrically with the interior cylindrical surface of the end housing 13 hereinbefore described. The ring portion 20 supported by and prefer-

ably formed integrally with the vertical arms 19 is adapted to support a spider having a ring portion 21 machined to fit the surfaces of the ring 20. Screws 20^a may be employed to secure these parts together. The spider is provided with a plurality of arms, two of which are shown in elevation at 22 and 23 and terminate in a centrally positioned and substantially cylindrical housing 24 in the lower end of which is mounted a ball bearing indicated generally at 25, the outer race 26 fitting within the lower interior of the housing 24. The interior race 27 of the ball bearing 25 is fitted upon a sleeve 28 which is downwardly extended so as to receive within its lower end the upper end 16^a of the armature shaft 16. The latter is rigidly connected with the sleeve 28 so as to form a driving connection by means of the pin 29 passing through the lower end of the sleeve 28. The upper end of the armature shaft 16 is thus rigidly supported and it will be noted that upon adjustment in an axial direction of the armature shaft 16 by means of the threaded cap 17 hereinbefore described the sleeve 28 with its associated ball bearing 25 may partake of a like movement, the housing 24 being suitably machined at its lower interior end as at 30 to permit of a movement in an axial direction of the upper supporting ball bearing 25.

The sleeve 28 is flanged at its upper end as at 31 so as to fix the position of the inner race 27 of the ball bearing and the latter is held in such position by the hub 32 of a fan indicated generally at 33, the hub 32 being threaded upon the sleeve and against the inner ball race 27 to securely lock the latter in position. A nut 34 is provided for locking the hub 32 of the fan 33 in position upon the sleeve 28. It will be noted that the construction above described thus permits of a convenient and ready assembly of the several parts.

It may at this point be noted that the fan 33, being thus rigidly mounted upon the shaft 16 of the motor being driven thereby, is effective to draw air downwardly between the arms 22 and 23 of the supporting spider for a purpose to be more clearly set forth hereinafter and thereupon discharges the air outwardly between the supporting arms 19 and downwardly through the effective or operative portions of the motor. The armature indicated generally at 35 and its associated field windings indicated generally at 36 are thus provided with an effective cooling current of air, which may thereupon exit through the lower end of the field frame 10 and through the spaces intervening the supporting lugs or standards 11. A cover plate 37 provided with an opening through which the motor shaft 16 may pass is mounted as by screws 38 upon

the interior end of the housing 13 whereby, together with the adjusting cap 17, the ball bearing supporting the lower end of the shaft 16 is substantially entirely encased and thus protected from dust and foreign matter which may be directed thereto by the current of air or otherwise.

The motor may be supplied with current from any suitable source, as for example a storage battery 39, and the circuit of the motor comprising the conductors 40 and 41 and hence the operation thereof is preferably controlled by means hereinafter to be more clearly described.

Taking up now in detail the cooling apparatus there is shown and generally indicated at 42 a compressor preferably of the rotary type mounted upon the flanged portion 43 and preferably integral with an upwardly directed extension 44 of the housing 24 hereinbefore described. The compressor 42 is preferably built up upon the flanged end 43 of the housing 44 and may comprise for example the substantially cylindrical wall portion 45 and an end or closing plate 46 secured together as by means of the bolts 47. The end plate 46 has an upwardly directed cylindrical extension 48 into the lower end of which the outer race 49 of a ball bearing generally indicated at 50 is adapted to be fitted. The inner race 51 is secured in any suitable manner to the upper end of the shaft 52 of the compressor. A cap 53 is threaded onto the cylindrical extension 48 of the end plate 46 and is adapted to close the bearing housing formed by the extension 48. The several parts forming the casing for the compressor 42 may be accurately machined so that when fitted upon the flanged portion 43 of the housing 44 supported by the spider arms 22 and 23 and placed in assembled relation as shown in Fig. 1, the upper ball bearing 42 will be in axial alignment with the lower ball bearing 25 which, as hereinbefore described, is by the construction employed also in alignment with the lowermost ball bearing 14—15.

The compressor shaft 52 is extended downwardly and is in driving connection with the motor shaft 16 as follows. In the upper end of the sleeve 28 there is pivotally supported a block 54 of a substantially rectangular cross-section, the block 54 being held in position by means of the pin 55 passing through it and through the sleeve 28. The lower end of the compressor shaft 52 is milled out as at 56 to provide an axially extending slot in the lower end thereof into which the block 54 may be received. The milled portion or slot 56 is, moreover, of sufficient extent so as to permit of a relative movement or sliding action to take place between the lower forked end of the shaft 52 and the sleeve 28 within which the lower end of the shaft 52 is received. The milled or slotted portion 56 of

the shaft thus not only insures a positive driving connection between the compressor shaft 52 and the motor shaft 16 but also permits of an axial adjustment of the motor shaft 16 by means of the cap 17 hereinbefore described to take place without affecting the compressor shaft 52 and its upper mounting. Furthermore, it may also be noted that the lower or forked end of the shaft 52 which straddles the block 54 preferably fits snugly within the sleeve 28 so that the lower end of the compressor shaft 52 is supported thereby and so that the ball bearing 25, supporting the upper end of the motor shaft 16 also forms the roller bearing for the compressor shaft 52.

The compressor 42 on being operated is adapted to compress, as will be more clearly set forth hereinafter, a volatile and condensable gas, such for example as sulphur dioxide, and in order to provide for adequate lubrication of the moving parts of the compressor a suitable lubricant having a different specific gravity from that of the sulphur dioxide is used and may, for example, take the form of a suitable petroleum oil. In order to prevent the leakage of the liquefied gas and lubricant downwardly and into the motor and its operative parts there is associated with the compressor and its driving shaft a suitable seal. This seal comprises in part a bushing 57 having suitably secured to its interior a corrugated expandible tube 58. The bushing 57 is adapted to be threaded into the housing 44 and the threaded connection indicated at 59 is made tight by means of a suitable packing or washer 60 interposed between the flanged end of the bushing 57 and a suitable shoulder on the interior of the housing 44. The interior diameter of the expandible tube 58 is materially greater than the diameter of the shaft 52 and is adapted to encase the latter, as is clearly shown in Fig. 1 of the drawings. At the lower end of the expandible tube 58 there is rigidly secured thereto a collar 61 shaped to form a housing for a second collar 62, which latter is preferably formed of a material of good wearing qualities such as steel for example and whose interior diameter is such as to permit the shaft 52 to rotate therein. The lower end face of the collar 62 indicated at 63 is accurately machined or surfaced to form a close fit with the upper end face of the sleeve 28 which preferably is also made of a material of good wearing qualities such as steel for example.

The lower end face 63 of the collar 62 which, as above noted, is fixed against rotation by its engagement with the collar 61 is held in tight contact with the upper end face of the sleeve 28 by reason of the tendency of the corrugated tube 58 to expand thus preventing any leakage which may take place between the shaft 52 and the collar 62 from

escaping to the exterior. Furthermore, sufficient liquid including lubricant will be supplied to the relatively moving end faces of the seal-forming collar 62 and sleeve 28 to effectively lubricate these surfaces against excessive wear. Any leakage that finds its way downwardly into the sleeve 28 is prevented from reaching the exterior or the moving parts of the apparatus by means of a diaphragm indicated at 64 in the interior of the sleeve 28 and interposed between the ends of the compressor shaft 52 and of the motor shaft 16. The diaphragm or seal 64 may be made of any suitable material such as, for example, lead or copper, and may be expanded by hammering for example into proper sealing position, a suitable circumferentially extending groove indicated at 65 being provided on the interior of the sleeve 28.

The tightness of the seal formed by the collar 62 and the end face of the sleeve 28 may be adjusted by adjusting the position of the motor shaft 16 and hence of the end face of the sleeve 28 in an axial direction by means of the adjusting cap 17 hereinbefore described.

The compressor 42 discharges the gas under relatively high pressure through the tube 66 from which it passes throughout an inner coil 67 and an outer coil 68 of a condenser. A series of copper sheets, indicated generally at 22^a and spaced from one another in a preferably radial manner, are fitted about the coils 67 and 68 and serve as cooling flanges for bringing about a more effective cooling of the fluid passing through the coils. The condenser coils and their associated cooling flanges form a substantially compact and annularly shaped condenser which preferably surrounds the compressor and is suitably supported upon the arms 22 and 23 of the supporting spider hereinbefore described. The fan 33 whose action has been hereinabove briefly described is effective to draw a current of air downwardly through the condenser and over the cooling flanges, thus making more effective the action of the condenser in condensing the compressed gas into liquid form. The liquefied gas passes from the condenser through the connecting tube 69 to an annular receiver 70 surrounding the condenser coils 67 and 68 and suitably supported upon the ring portion 21 of the supporting spider. The receiver in being thus positioned is also affected by a current of air drawn through the condenser which it surrounds and the cooling is thus made highly effective.

In the receiver 70 the liquid is permitted to accumulate and since as above noted the compressor is supplied with a suitable lubricant, a material quantity of the lubricant will pass off with the gas and with the gas will accumulate in the receiver 70. The lu-

bricant and the condensed gas, however, are of different specific gravities and hence a separation may take place within the receiver 70. One of the features of this invention resides in the provision of means for bringing about an effective separation of the lubricant from the condensed gas. In Figs. 3 and 4 of the drawings the receiver 70 is shown on a smaller scale and it will be noted that adjacent the tube 69 through which the mixed lubricant and condensed gas is discharged from the condenser into the receiver 70 there is provided a downwardly extending baffle plate 71 extending laterally between the two annular walls of the receiver 70 and extending downwardly, as more clearly shown in Fig. 4, to contact with the bottom of the receiver 70.

Owing to the differing specific gravities of the lubricant and the condensed gas, and assuming that sulphur dioxide and oil are employed as above noted, the sulphur dioxide, being of greater specific gravity than the lubricant or oil, will separate into a lower stratum indicated at 72 and the lubricant will accumulate in an upper stratum indicated at 73. The baffle plate 71 extends downwardly to the bottom of the receiver and with the walls of the receiver forms a substantially annular path of flow from one side of the plate 71 to the other side. On this other side of the baffle plate there extends a tube 74 in an upward direction, as is clearly shown in Fig. 4, and to such extent as to extend into the upper stratum 73 of lubricant, in order to permit the latter to be withdrawn. The condensed gas in the stratum 72 is withdrawn from the receiver by the tube 75 positioned adjacent the baffle 71 but on that side thereof opposite the inlet tube 69, and has a portion 75^a extending downwardly into the receiver and into the lower stratum 72 of condensed gas. The tube 74 (Fig. 4) is extended so as to enter a cap 53 (see Fig. 1) at the upper end of the compressor housing so as to withdraw the lubricant from the stratum 73 and supply it to the moving parts of the compressor. A member 74^b is detachably mounted in the cap 53 and is provided with a suitable orifice which serves to limit the flow of lubricant to the desired extent.

Considering now the action of separation which takes place in the receiver, it will be noted that the mixed condensed gas and lubricant have to pass circumferentially or throughout the entire extent of the annular path provided by the concentric walls of the receiver in order to get from the inlet side of the baffle plate 71 to the other or outlet side thereof. The mixed fluids thus have to travel throughout their relatively great path and there is thus allowed a sufficiently great length of time during this passage for an effective separation by gravity to take place.

As the mixed liquids continue their travel throughout the path provided therefor by the receiver, the separation becomes progressively more complete so that by the time the condensed gas and the lubricant have reached the outlet side of the baffle plate 71 the two strata 72 and 73 are well defined. From these two strata the sulphur dioxide and the lubricant are withdrawn by the tubes 75^a and 74 respectively.

It may also be noted that this construction permits the desirable concentration of the connecting tubes or conduits at substantially a single point and thus makes for a more compact construction.

Considering now the steps in the cycle through which the cooling gas passes, the condensed gas after being withdrawn from the lower stratum 72 through the tube 75^a passes through an expansion device comprising a plurality of expansion units or orifice members which are preferably housed in serial relation in the tube 75. Thus, referring to Fig. 5, there is shown a section of the tube 75 in which are fitted a plurality of expansion units 76 each provided with an orifice 77. Referring to Figs. 6 and 7 in which the construction of a single expansion unit is shown on enlarged scale, it will be seen that each unit 76 comprises preferably a substantially cylindrical chamber forming portion 76^a open at one end and closed at the other by means of the end wall 76^b in which the orifice 77 is substantially centrally positioned. Turning now to Fig. 5 it will be seen that when a plurality of such expansion units 76 are arranged serially within the tube 75 there is formed a series of expansion chambers separated, adjacent chambers being connected through the orifices of the preceding unit. Thus the expansion from a relatively high pressure to a relatively low pressure to bring about the desired reduction in pressure takes place in a series of successive expansions through a series of orifices whose dimensions may be sufficiently large to prevent foreign matter from clogging the orifices and from affecting the operation of the apparatus. The drop in pressure between adjacent expansion chambers or units is relatively small since the orifices employed are as above noted of materially large dimensions, but the drop in pressure and hence the drop in temperature between the first and the last expansion is relatively great. The desired drop in temperature is thus obtained with larger expansion orifices than would be necessary were the entire expansion to take place through a single orifice. The operation of the expansion device is thus made highly dependable and reliable.

The provision, furthermore, of a plurality of serially arranged orifices permits the flow of refrigerating liquid throughout the en-

tire cycle to be readily maintained within a predetermined limit dependent upon the rate at which the cooling is intended to be carried on. For example, with a given size 5 of orifice, the rate of flow for the desired rate of cooling may be governed by the number of expansion units employed.

Furthermore, it should be noted that each 10 expansion unit 76 is of simple construction and may, for example, be readily stamped or punched out of sheet metal thus insuring an inexpensive cost of manufacture. It should also be noted that the series of expansion units are readily assembled or 15 placed in serial relation within the tube 75 which preferably forms one of the usual pipe or tube connections and thus additional tubing and complications are avoided. The tube 75, furthermore, in which the expansion units are mounted may readily be bent, if desired, to form the desired connections without impairing the action of the expansion devices therein positioned.

After passing from the receiver 20 through the expansion units 76 in the tube 75, the expanded gas is led by the tube 75 (see Fig. 2) to a coil 78 whose other end terminating in the tube 79 is connected to the inlet side of the compressor 42 (see Fig. 1), 25 through an extension of the tube 79.

The coil 78 is mounted within a suitable sheet metal container 80 insulated upon its exterior by means of a suitable heat-insulating material 81 suitably supported in relation thereto as by means of the sheet metal casing 82 supported in turn upon a suitable base 83. The sheet metal container 80 and the casing 82 are adapted to support a collar 84 formed at its upper end to receive a 30 rubber ring 85 in which may be rested an inverted water bottle indicated fragmentarily at 86. The container 80 is preferably tapered as shown in Fig. 2 of the drawings, and the coil 78, similarly tapered, is encased in 35 a suitable material of relatively high heat-conductivity, such as for example lead. Thus, as indicated in Fig. 2 of the drawings, the coil 78 is imbedded or packed in lead as indicated at 87, thus forming an interior 40 lining for the container 80 and substantially similarly tapered. There is thus formed a chamber whose interior walls are substantially continuous and unbroken surfaces and of sanitary construction. Furthermore, the 45 spaces that would otherwise intervene the turns of the coil 78 are avoided so that the accumulation of foreign matter therein is effectively precluded.

The tapered chamber thus formed as above 50 described is adapted to receive a substantially similarly tapered receptacle 80^a fitting snugly therein so that the walls of the receptacle 80^a are in snug contact with the highly 55 heat-conductive lining 87 in which the coil 78 is imbedded. From the water bottle 86

the water will accumulate in the receptacle 80^a and will be maintained at the desired level therein. At a suitable point in the lower portion of the walls of the receptacle 80^a there is provided a bushing 80^b adapted 70 to receive the inner threaded end of the conduit 91 passing through a suitable opening provided in the lining 87, the container 80, the casing 82 and the heat-insulating material 81 interposed therebetween. Upon the 75 outer end of the tube 91 may be mounted a suitable faucet for withdrawing the water as desired from the receptacle 80^a. The faucet with its connecting tube 91 may be readily removed by unscrewing from the 80 bushing 80^b upon the interior of the receptacle 80^a so that the receptacle 80^a may be readily removed for purposes of cleaning both the receptacle and the interior parts of the cooling apparatus. 85

In order to maintain the cooling action of the apparatus substantially uniform and to maintain such action within desirable limits there is mounted in the lower part of the container 80 a thermostatic vessel 88 whose 90 construction is preferably substantially conical in shape, as shown in Fig. 2 of the drawings. The substantially conically shaped vessel 88 provides a suitable interior chamber from which a tube 89 leads to a pressure-controlled switch indicated diagrammatically at 90 and adapted to control the circuit of the motor. Thus, in Fig. 2 of the drawings the conductors 40 and 41 of the electric circuit of the motor are brought to 95 the switch 90 to open or close the circuit in accordance with the fall or rise of temperature of the water within the receptacle 80^a between predetermined limits.

As the thermostatically controlled switch 100 forms no part of this invention it has been merely diagrammatically illustrated, and as for the details thereof reference may be had by way of example to my co-pending application filed February 15, 1922, Serial No. 110 536,611. It may briefly be noted, however, that the pressure-controlled switch indicated 105 diagrammatically at 90 is adapted to be responsive to changes in pressure, for example of a suitable fluid, as a result of the changes of temperature taking place within the thermostatic vessel 88. According to one of the 110 features of this invention, means are provided for maintaining the thermostatic vessel 88 in intimate thermal contact with the receptacle 80^a, and referring to Fig. 2 of the drawings it will be seen that the vessel 88 is of conical exterior shape and that the bottom 80^c of the receptacle 80^a is also of 115 conical shape. The vessel 88 is supported upon the abutment 92 to which it is connected by means of a spring 93 tending to urge the vessel 88 in an upward direction. The tube 89 connecting the pressure-operated 120 switch 90 with the vessel 88 may be of 125

any suitable flexible construction to permit the movement of the vessel 88 to take place in response to the action of the spring 93.

The receptacle 80^a on being inserted within 5 the lined container 80 is, as above noted, placed in intimate contact with the lining 87 in which the cooling coil 78 is imbedded, and since the coacting walls are tapered the snug contact thereof is assured to bring the parts 10 in intimate thermal relation. Furthermore, upon the insertion of the receptacle 80^a the thermostatic vessel 88 is automatically seated within the cone-shaped bottom 80^c of the receptacle and is held not only in such seated 15 position but also in close contact with the bottom of the receptacle in response to the action of the spring 93. The thermostatic vessel 88 is thus also maintained in intimate contact with the water to be cooled so 20 that the action of the switch 90 may be accurately and reliably controlled thereby.

It will thus be noted that there has been provided in this invention an apparatus in which the several objects above set forth, as 25 well as others, are attained and in which many advantages are successfully achieved. It will furthermore be noted that there has been provided apparatus in which the several parts may be readily and accurately 30 assembled for operation and that when so assembled a unitary and substantially self-contained cooling apparatus is provided. Furthermore, the several parts are of rugged construction and are of convenient and ready 35 adjustment for most effective mechanical operation. It may also be noted that there has been provided apparatus of an exceedingly practical construction conducive to inexpensive manufacture and durable and rugged 40 operation when in use.

I make no claim herein to the structural features per se of my invention relating to the prime mover and condenser, having made the latter features of my invention the subject-matter of a divisional application, Serial No. 45 753,924, filed December 4, 1924; nor do I make herein specific claim to the structural features per se illustrated in Fig. 2 herein, having made such features the subject-matter 50 of a divisional application, Serial No. 753,925, filed December 4, 1924.

As many possible embodiments might be made of the above invention and as many changes might be made in the embodiment 55 above set forth, it is to be understood that all matter hereinafter set forth or shown in the accompanying drawings is to be interpreted as illustrative and not in a limiting sense.

60 I claim as my invention:

1. In apparatus of the nature of that herein described, in combination, a compressor, a condenser connected to receive 65 condensed fluid and lubricant from said compressor, a receiver providing an annu-

lar path of flow adapted to receive condensed fluid and lubricant from said condenser and to permit the separation of the lubricant from the condensed fluid therein, means associated with said receiver for causing said condensed fluid and said lubricant to travel throughout substantially the entire extent of said annular path through said receiver, and means adapted to return said separated lubricant to the moving parts 70 of said compressor.

2. In apparatus of the nature of that herein described, in combination, a compressor, a condenser adapted to receive compressed fluid and lubricant from said compressor, a substantially annularly shaped receiver having a connection with said condenser for receiving condensed fluid and lubricant therefrom and adapted to permit the separation of the lubricant from the 80 condensed fluid to take place therein, an outlet positioned adjacent said intake connection for discharging the separated condensed fluid from said receiver, means interposed between said outlet and said intake 85 connection adapted to cause said fluids to travel throughout substantially the entire extent of said annularly shaped receiver, and means adapted to return the separated lubricant to the moving parts of said compressor and connected to said receiver substantially adjacent said outlet.

3. In apparatus of the nature of that herein described, in combination, a compressor, a condenser adapted to receive compressed fluid and lubricant from said compressor, a receiver having two substantially circular, concentric and spaced walls and having an inlet connection for receiving condensed fluid and lubricant from said condenser, a baffle plate interposed between said concentric walls of said receiver and positioned adjacent said inlet connection, an outlet connected to said receiver adjacent said baffle plate and on the side thereof remote from said inlet connection for withdrawing condensed fluid from said receiver, and a second outlet positioned in proximity to said outlet connection and on the side of said baffle plate remote from said inlet connection for returning separated lubricant to said compressor, said baffle plate causing said condensed fluid and lubricant to travel from one side of said baffle plate throughout substantially the entire extent of the annular path provided by said concentric walls of said receiver to said outlet connections on the other side of said baffle plate whereby a separation of the lubricant from said condensed fluid may take place.

4. In apparatus of the nature of that herein described, in combination, a plurality of expansion units each made of sheet metal and shaped to provide an elongated cylindrical chamber forming portion having 130

one end open and a closing wall portion provided with an expansion orifice at the other end and adapted to be arranged in axial alignment, and means for retaining said units in axial alignment.

5. In apparatus of the nature of that herein described, in combination, a plurality of serially arranged expansion units each comprising a sheet metal member 10 stamped to form a substantially cylindrical chamber forming portion open at one end and having a closing wall portion provided with a substantially centrally positioned orifice at the other end, and a substantially cylindrical casing for mounting and retaining said units in serial relation.

6. In apparatus of the nature of that herein described, in combination, a motor having a frame provided with vertically extending supporting arms, a compressor driven by said motor, a condenser coil for receiving compressed fluid from said compressor and a curved receiver for receiving condensed fluid from said condenser, said 20 condenser coil and said receiver being arranged concentrically and supported by said arms, and means driven by said motor for passing a cooling fluid in thermal contact with said condenser.

30 7. In apparatus of the nature of that herein described, in combination, a motor having a vertically extending driving shaft and having a frame provided with vertically extending supporting arms, a fan on said 35 motor shaft and positioned within said supporting arms, a compressor driven from said motor shaft, a condenser coil for receiving compressed fluid from said compressor, a curved receiver for receiving condensed 40 fluid from said condenser, said condenser coil and said receiver being arranged substantially concentrically, and means for supporting said compressor, said condenser coil and said receiver from said supporting arms, 45 said condenser being thereby positioned to be affected by said fan.

8. In apparatus of the nature of that herein described, in combination, a motor having a vertically extending driving shaft 50 and provided with an apertured frame member spaced from said motor in the direction of said driving shaft, a compressor driven from said driving shaft, a condenser coil for receiving compressed fluid from said 55 compressor and supported by said apertured frame member, a receiver for receiving condensed fluid from said condenser coil, and a fan on said driving shaft positioned in the space between said frame member and 60 said motor and arranged to cause a flow of air through said apertured frame member.

9. In apparatus of the nature of that herein described, in combination, a motor having a vertically extending driving shaft 65 and provided with an apertured auxiliary

frame member, a compressor driven from said driving shaft, a condenser coil for receiving compressed fluid from said compressor, a curved receiver for receiving condensed fluid from said condenser coil, said 70 condenser coil and said receiver being arranged substantially concentrically and being supported by said apertured frame member, and a fan driven by said motor and arranged to cause a flow of air through said 75 apertured frame member.

10. In apparatus of the nature of that herein described, in combination, a main frame provided with a bearing at one end thereof, a prime mover mounted within said 80 main frame and having one end of its shaft rotatably supported in said end bearing, a secondary frame detachably secured to said main frame and having a bearing therein for supporting rotatably the other 85 end of said prime mover shaft, compressing means driven by said prime mover, means for receiving fluid compressed by said compressing means and adapted, upon being cooled, to permit condensation of said 90 compressed fluid therein, means for receiving condensed fluid from said last-mentioned means, one of said means being supported by said secondary frame, and means controlled by said prime mover for passing a cooling 95 fluid in thermal contact with said condenser.

11. In apparatus of the nature of that herein described, in combination, a main frame provided with a bearing at one end thereof, a prime mover mounted within said 100 main frame and having one end of its shaft rotatably supported in said end bearing, a secondary frame detachably secured to said main frame and having a bearing therein for supporting rotatably the other end of 105 said prime mover shaft, compressing means driven by said prime mover, means for receiving fluid compressed by said compressing means and adapted, upon being cooled, to permit condensation of said compressed 110 fluid therein, means for receiving condensed fluid from said last-mentioned means, at least two of said means being supported by said secondary frame, and means effective 115 when said prime mover is operating for passing a cooling fluid in thermal contact with said condenser.

12. In apparatus of the nature of that herein described, in combination, a main frame provided with a bearing at one end thereof, a prime mover mounted within said 120 main frame and having one end of its shaft rotatably supported in said end bearing, a secondary frame detachably secured to said main frame and having a bearing therein for supporting rotatably the other end of 125 said prime mover shaft, compressing means driven by said prime mover, means for receiving fluid compressed by said compressing means and adapted, upon being cooled, 130

to permit condensation of said compressed fluid therein, means for receiving condensed fluid from said last-mentioned means, one of said means being supported by said secondary frame, and a fan on said prime mover shaft and intermediate of the bearings thereof for passing a current of air in thermal contact with said condenser.

13. In apparatus of the nature of that herein described, in combination, a main frame having mounted therein a prime mover having a driving shaft, a secondary frame detachably secured to said main frame, a compressor supported by said detachable secondary frame and having means forming a detachable connection between its shaft and the prime mover shaft, means for receiving fluid compressed by said compressor and adapted upon being cooled to permit condensation of said compressed fluid therein, means for receiving condensed fluid from said last-mentioned means, one of said means being supported by said detachable secondary frame, and a fan driven by said prime mover for passing a current of air in thermal contact with said condenser.

14. In apparatus of the nature of that herein described, in combination, a main frame having mounted therein a prime mover having a driving shaft, a secondary frame detachably secured to said main frame and supporting a compressor, the

shaft of the compressor and said prime mover driving shaft being provided with a driving coupling arranged to effect or disrupt the driving connection therebetween according as said secondary frame is assembled with or is removed from said main frame, means for receiving fluid compressed by said compressor and adapted upon being cooled to permit condensation of said compressed fluid therein, means for receiving condensed fluid from said last-mentioned means, one of said means being supported by said secondary frame, and means for passing a cooling fluid in thermal contact with said condensing means.

15. In apparatus of the nature of that herein described, in combination, means adapted to hold a liquefied fluid, a heat-absorbing device, a pipe forming a connection therebetween, and expansion means comprising a plurality of serially arranged individual expansion units inserted directly in said pipe, each unit comprising an end wall portion having an expansion orifice therein and a substantially cylindrical chamber-forming portion integrally formed with said end wall portion and extended in a direction away from said end wall portion.

In testimony whereof, I have signed my name to this specification this 30th day of January, 1922.

GEORGE E. HULSE.
